UNITED STATES PATENT OFFICE.

JOHN H. BARTH, OF TERRE HAUTE, INDIANA.

LAMP FOR DECORATING AND ILLUMINATING PURPOSES.

SPECIFICATION forming part of Letters Patent No. 373,958, dated November 29, 1887.

Application filed April 21, 1887. Serial No. 235,634. (No model.)

To all whom it may concern:

Be it known that I, JOHN H. BARTH, of Terre Haute, in the county of Vigo and State of Indiana, have invented a new and useful 5 Improvement in Lamps for Decorating and Illuminating Purposes, of which the following is a full, clear, and exact description.

This invention, while applicable to various decorative and illuminating purposes, is more 10 particularly designed to take the place of candles on Christmas-trees in churches, schools, or dwellings; and the invention consists in a candle-like lamp provided with special means for its suspension and attachment and with a peculiarity-constructed burner adapted to carry 15 a globe-shade, substantially as hereinafter described, and pointed out in the claims.

Reference is to be had to the accompanying drawings, forming a part of this specification, 20 in which similar letters of reference indicate corresponding parts in all the figures.

Figure 1 represents a longitudinal view, in perspective, of a lamp embodying the invention with its globe-shade in position. Fig. 2 25 is a vertical section of the same in a plane at right angles to Fig. 1, and Fig. 3 is a top or plan view of the lamp with the globe removed.

A indicates the body of the lamp of cylindrical contour, and which may be a simple glass vial having an exterior screw-thread, b, on its upper end or neck, or which may be made of any other suitable material.

Fitting or screwing onto the neck portion 30 b of the body is a mainly conical-shaped burner or burner-cap, B, which may be of metal, and is adapted to hold or receive a wick, C, down through it. The base portion of said burner is cylindrical, to fit the neck b of the 35 body, and is provided with a lower ring or rim, c, while the upper portion of the burner is tubular, to form a guide and support for the wick; but the burner, taken as a whole, is what may be termed a "conical" one, which 40 shape or construction when united with the cylindrical body A gives to the lamp a candle-like appearance. Furthermore, the conical-shaped burner has a series of exterior tapering ribs or ridges, d d, down it to provide 45 for the easy slipping to its place and secure hold when in position of a globe or partly globular shade, D, which may be of any de-

sired color. The spaces between these ribs serve to give a free supply of air to the exposed portion of the wick within the shade 55 for the purpose of keeping up combustion.

Pivoted to the ring or rim c of the burner B is a hook, G, to which may be attached a wire or other flexible connection, S, for hanging and securing the lamp as required, the 60 hook G providing for hanging the lamp almost instantaneously on any of the twigs or branches of a Christmas-tree, for instance, while the wire S will serve, by a single twist or so about the twig or branch, to secure the lamp and give perfect safety even when the lamp is hung upon the extreme end of a branch of the tree. This removes a great difficulty heretofore experienced in using candles on Christmas-trees, and by making the globes or shades of the several 65 lamps in use at a time of different colors a greatly-improved effect will be produced.

Lamps constructed as described may be used to advantage for various decorative and illuminating purposes. They will be found especially advantageous, however, for illuminating and decorating Christmas-trees, as they will be very much safer than candles, cheaper to use, cleaner, give a steadier and brighter light, have a much better effect, will burn longer, 70 be actual ornaments in themselves, do away with the usual weighty balances—such as are attached to candles on trees to keep them upright and which weigh down the branches. They also can be more easily lighted than candles and in other respects have the advantage over candles for the purpose herein named, 75 but in none more importantly so than in the safety which attaches to them as compared with candles, that expose the tree to taking 80 fire and that have been the cause of so many lamentable accidents.

To avoid offensive odor from the oil burnt in the lamps the wicks may be steeped in cider vinegar, and to give a small neat light the 85 wicks should be cut close to the tubes of the lamps or their burners.

Having thus fully described my invention, I claim as new and desire to secure by Letters Patent—

1. The combination, with the glass vial A, having integral screw-threads at its open end, of the conical burner B, made in a single piece and formed with the central wick-passage and

having a suspension-wire pivotally connected at its ends to the burner at opposite sides and formed with the hook G between its ends, substantially as set forth.

5 2. As a new article of manufacture, the conical lamp-burner B, formed with the tubular wick-holding passage, the external integral longitudinal ribs, *d*, the screw-threaded neck *b*,

and the suspension-hook G, having two arms pivotally connected to opposite sides of the neck, substantially as set forth.

JOHN H. BARTH.
